UNITED STATES PATENT OFFICE.

WINFRED P. SHEPHERD, OF RIVERSIDE, CALIFORNIA, ASSIGNOR TO GEO. D. PARKER,
OF RIVERSIDE, CALIFORNIA.

TREE-PROP.

1,078,004.

Specification of Letters Patent. Patented Nov. 11, 1913.

Application filed February 16, 1912. Serial No. 678,064.

To all whom it may concern:

Be it known that I, WINFRED P. SHEPHERD, a citizen of the United States, residing at Riverside, in the county of Riverside and State of California, have invented new and useful Improvements in Tree-Props, of which the following is a specification.

This invention relates to adjustable prop brackets.

Methods of propping tree limbs have progressed from the use of stays connecting various limbs, which required a great amount of time and labor to emplace, to the use of poles or props which may be quickly set up, and having some sort of adjustable brackets thereon on which the braced limbs may rest. My invention relates particularly to the latter type. Throughout this development, certain considerations governed those making improvements therein. One of the principal aims has been to obtain a device which can be quickly put in place or removed. Of greater importance is the necessity for supporting limbs without damaging the bark or wood, as it would not do in saving the produce of one season to destroy the usefulness of the limb in succeeding seasons. Such brackets have comprised many forms, but generally those made of wire are most cheaply produced, but are more prone to damage the bark of trees (by reason of the small breadth of the supporting surfaces) than the sheet metal devices.

It is therefore an object to provide an improved adjustable bracket enabling the use of wire where most desirable, and permitting the use of sheet metal conveniently and economically where essential for directly engaging the limb to be supported.

It is an object of this invention to provide an improved adjustable bracket, therefore, of such construction as will enable the combining of the advantages of both the sheet metal and wire construction in one device.

A further object is to provide an anchoring means for securing the bracket to a pole, which will be quickly adjustable yet positive in operation, and in which the weight of a supported limb will act to secure it in place positively.

Another object is to enable the pivotal at-

tachment of a sheet metal limb supporting hook to a wire anchoring yoke in a simple manner.

A still further object is to adapt the device to be folded into a small space, and allow a plurality of them to be nested for shipment in a compact form.

Other objects and advantages will be apparent from the following description and from the drawings, in which—

Figure 1 is a side view of the device engaged upon a pole and supporting a limb, Fig. 2 is a detail perspective view of the device detached, Fig. 3 is a detail view showing a plurality of the devices nested.

There is illustrated a pole 10, having engaged therewith a bracket comprising the securing or anchoring yoke 11 and the swiveled bracket hook 12, in which there rests a limb 13.

The anchor yoke comprises a single piece of wire of suitable weight, preferably galvanized or otherwise treated to protect it from corrosion; the wire being bent into approximately U-shaped form, thus providing the rectilinear bight portion 14 from which spring the parallel arms 15 at right angles to the bight. The extremities of the arms are sharply pointed and recurved inwardly in spaced relation approximately parallel to the arms and suitably spaced therefrom to form spurs 15', so that they may readily engage the prop when projected into the yoke.

The bracket hook comprises a plain rectangular blank of sheet metal or other material suitable for the use, the corners of which blank may be rounded at two or more corners. Two longitudinally extending loops 16 are pressed toward the back side of the hook, from near one end at and including respective longitudinal edge portions of the blank, which is curved continuously from these loops toward the farther end of the blank and forwardly, to form the hook. The intermediate portion of material between the loops 16 is pressed toward the inner face of the hook forming a loop 17 opposed in direction to those 16, and avoiding the stretching and weakening of the metal in the loops 16 which would occur if the middle portion were left unbent. Be-

ginning immediately adjacent the loop 17 the material of the hook is transversely curved toward the outer face, making the inner surface convex. In the formation of this transverse curvature the edge portions of the metal are stretched so that they resist the return of the device to its original flat form. Thus in addition to providing a rounded surface adapted to support a limb without damage to the bark the hook is greatly strengthened. As the tendency of the hook to flex or bend under excessive weight supported thereby is not manifest immediately adjacent the loops, it is made possible to begin this transverse curvature gradually so that rupture of the metal is not made a liability.

The hook receives the bight portion of the yoke 11 revolvably within the loops, the middle one going on one side and the side loops engaging over the other side of the bight, and it will of course be understood that it is necessary to so engage the wire before the bending thereof into its final shape. The small portion of the blank projecting outwardly of the loops opposite the hook may be turned rearwardly as at 18 whereby it forms a chock or locking means, as will be explained.

30 In use, a pole prop 10 is used the transverse dimension of which in one direction is slightly less than the distance between the arms 15 and in the other direction a little less than the distance between the points of the spurs 15' and the top of the chock 18 when the hook is lifted to bring the bill 19 into a line at right angles to the plane of the yoke. Thus when the hook and yoke are held in the last mentioned relative position the yoke may be slipped easily over the pole to any desired position, and when at the proper point, by lowering the hook, the chock 18 strikes against the pole, embedding the spurs 15' securely in the pole; the outer end of the chock under this movement finally passes above the plane of the yoke, whereby in which lies the direction of force acting between the spurs and the fulcrum of the hook, and the resultant force acting upon the chock through the pole tends to hold the hook against casual movement into adjusting or released position, and also holds the hook against the pole preventing any loose play thereof. However, in addition to the chock 18, or without it, it will be noted that the hook itself performs a cam bearing action upon the pole tending to force the spurs 15' into the pole under the weight carried by the hook, and by providing the spurs or teeth 20 on the rear side thereof a downward pull will be exerted by the hook upon the yoke under the effect of pressure on the hook. In this way the hook is made to adapt itself to poles of widely various thicknesses, and the expense or difficulty of providing

special size of props avoided. It may even save the cost of obtaining milled lumber entirely, as ordinary sapling poles may be used, the hook automatically accommodating itself to the variances in diameter of such a pole and engaging it at any desired point to draw the yoke spurs thereinto.

70 A most important advantage of the device is the compact manner in which it may be packaged, the completed devices occupying but little more than the space which would be required for the hooks alone, as may be seen in Fig. 3, where it will be seen that the hooks are made so as to occupy the space within the yokes when superposed one upon another.

75 It is of course appreciated that various methods for making the hook rigid may be employed in addition to that before described, such for instance, as the longitudinally extending ribs 22 formed on the inner side of the hook. The hook may also be transversely curved at the same time, as shown, whereby the rigidity is considerably augmented and the side edges of the hook 80 so disposed as to not engage the limbs supported.

85 What is claimed is:

1. In a device of the class described, the combination with an anchor yoke formed of wire comprising a bight portion and arms adapted to embrace a pole, the ends of the arms being recurved to form pole engaging spurs; of a sheet metal bracket hook having a loop portion formed therein at one end and engaged revolvably with the bight of said yoke, the hook being so formed as to present a cam portion toward a pole engaged with the yoke, for embedding said spurs in the pole under application of weight 90 to the hook.

95 2. In an adjustable bracket for tree props, the combination with a wire anchor yoke adapted for engagement with a prop and having a rectilinear bight, of a sheet metal limb engaging hook having a rounded central portion adapted to engage a limb for support thereof without abrasion, and having longitudinal slits adjacent one end, parts of the metal of the hook intermediately of and laterally adjacent the slits being respectively bowed outwardly and inwardly, the said bight being engaged through the slits and held revolvably between the opposed bowed portions of the hook.

100 3. A device of the class described comprising a pole engaging yoke adapted for free sliding movement over a pole, and a limb supporting bracket element pivoted thereon and adapted to lie within the yoke at times, said bracket being formed for nesting in a similar one with the yokes in superposed relation therearound.

105 4. A device of the class described comprising a pole engaging yoke adapted to slid-

ably embrace a pole and having inwardly directed spurs adapted to engage a pole therewith when forced thereagainst, a bracket hook pivoted on the yoke opposite the spurs and in the direction of their points, said hook having a cam portion adapted to engage a pole under application of weight to the hook to draw upon the yoke to embed the spurs in the pole, and tooth elements on 10 the cam portion directed toward the pivot

whereby the yoke will be forced into diagonal position on the pole.

In testimony whereof I have hereunto set my hand in presence of two subscribing witnesses.

WINFRED P. SHEPHERD.
